CLAIM

The ornamental design for a wide brim hat with opening, as shown and described.

DESCRIPTION

FIG. 1 is a perspective view showing my new design for a wide brim hat with opening;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear view of the wide brim hat in an alternate position.

The broken lines in the drawing figures depict portions of the wide brim hat with opening which form no part of the claimed design.

The shade lines on the surfaces of the wide brim hat with opening define the contours of the hat and do not reflect a particular surface ornamentation or material.
